CLAIM

The ornamental design for a display device for furniture as shown and described.

DESCRIPTION

FIG. 1 is a front, right perspective view of a display device for furniture showing our new design with the display portion in a lowered position;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view of the display device for furniture of FIG. 1, shown with the display portion in a raised position;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is an enlarged view of portion "15" of FIG. 13; and, FIG. 16 is an enlarged view of portion "16" of FIG. 13.

The dash-dash broken lines illustrate portions of the display device for furniture that form no part of the claimed design. The dot-dot-dash broken lines illustrate the boundaries of the enlarged views and form no part of the claimed design.
